CLAIM

The ornamental design for a storage device, as shown and described.

DESCRIPTION

FIG. 1 is a bottom plan view of a storage device showing the new design.

FIG. 2 is a top plan view thereof.

FIG. 3 is a perspective view thereof.

FIG. 4 is an exploded perspective view thereof.

FIG. 5 is a side elevation view thereof.

FIG. 6 is a side cross-section view thereof, taken along line 6-6 of FIG. 5.

FIG. 7 is an exploded side elevation view thereof.

FIG. 8 is an exploded side cross-section view thereof, taken along line 8-8 of FIG. 7.

FIG. 9 is a perspective view thereof, shown in an environment of use.

FIG. 10 is an exploded perspective view thereof, shown in an environment of use; and,

FIG. 11 is a perspective view thereof, shown with environmental subject matter.

Broken lines illustrate portions of the storage device that form no part of the claimed design. The broken line showing of a phone in FIGS. 9 and 10 depicts environment for the storage device that form no part of the claimed design. The dot-dash lines illustrate exploded views of the storage device in FIGS. 4, 7, 8, and 10 that form no part of the claimed design.

1 Claim, 11 Drawing Sheets
